UNITED STATES PATENT OFFICE.

ADDREN H. YOUNG, OF NASHVILLE, TENNESSEE.

COIN SEPARATOR AND ASSORTER.

Application filed April 14, 1923. Serial No. 632,069.

To all whom it may concern:

Be it known that I, ADDREN H. YOUNG, a citizen of the United States, residing at Nashville, in the county of Davidson and State of Tennessee, have invented certain new and useful Improvements in Coin Separators and Assorters, of which the following is a specification, reference being had to the accompanying drawings.

10 This invention relates to means for separating and assorting coins of various denominations, and particularly to machines of this character designed to receive mixed coins in bulk and by a series of screens assort the coins and discharge them into the proper discharge spouts.

One of the objects of the invention is to provide means whereby the set of screen trays upon which the coins are discharged and by which they are assorted may be given a very rapid lateral reciprocating movement which will act to shift the coins around in the trays and eventually cause the assorting of the coins by the several trays.

25 A further object is to provide means whereby while the trays are reciprocating all of the trays may be tipped to a discharge position to discharge the coins therein into the proper coin chutes, the reciprocation of the trays acting to cause the downward movement of the coins on the screens and into the proper discharge chute.

Another object is to provide gates at the discharge ends of the several screen trays, which gates act to prevent the discharge of the coins before the coins have been fully assorted and before the series of trays have been tipped, and provide means for automatically opening these gates when the trays are tipped so as to permit the discharge of coins therefrom.

Still another object is to provide a machine of this character which is readily adapted to separate and assort other coins of a few denominations or coins of many denominations.

A still further object is to provide means whereby the trays may be supported for transverse reciprocation when they are in a horizontal position and also support the series of trays for transverse reciprocation when the trays are tilted.

A further object is to provide means for taking up the shock incident to the transverse reciprocation of the trays.

Other objects have to do with the details of construction and arrangement of parts as will appear more fully hereinafter.

My invention is illustrated in the accompanying drawings, wherein:

60 Figure 1 is a perspective view of a coin separator and assorter constructed in accordance with my invention;

Figure 2 is a longitudinal sectional view through the coin assorter, showing the assorting trays tipped in dotted lines;

Figure 3 is a horizontal section on the line 3—3 of Figure 2;

Figure 4 is a section on the line 4—4 of Figure 2;

Figure 5 is a detail fragmentary side elevation of the trays showing the gate operating means;

Figure 6 is a section on the line 6—6 of Figure 2;

Figure 7 is a diagrammatic view illustrating a coin assorter having six trays instead of three and showing in dotted lines the manner in which these trays operate to discharge coins into the several chutes;

80 Referring to these drawings, 10 designates a rectangular casing which may be of any suitable length and width and may be made of any suitable material properly braced, and has mounted within it a transverse shaft 11 which is mounted in suitable bearings in the casing for rocking movement but is held from longitudinal movement. Disposed within the casing above this shaft are a series of trays, shown as three in number and designated 12, 13 and 14, these trays being mounted in a suitable frame and each tray having a perforated bottom constituting a screen, these perforated bottoms being designated 15, 16 and 17. The bottom of 85 the lowest tray is not perforated. The bottom of the first tray has perforations slightly smaller than the largest coins to be handled, the bottom of the second tray has perforations larger than the smallest coins to be 90 handled, and, as before remarked, the bottom 17 of the lowest tray is imperforate. The bottom 17 of the lowest tray is imperforate. Thus it will be understood that when a mass of coins is disposed upon the top tray and the series of trays are laterally reciprocated, 95 as before stated, the smallest coins will drop through the bottom 15 and will also pass through the bottom 16 and land upon the bottom 17, the largest coins will be held from passage through the screen 15, while 100

105 110

the coins next in size will be held upon the screen 16, being too large to pass through the openings thereof.

I have illustrated screens arranged to separate and assort nickels, dimes and quarters, but it will be understood that more screens may be used so as to assort half dollars, quarters, nickels, dimes and pennies or any other combination of coins of different sizes.

The frame within which the several screens or trays are mounted is designated 18 and this frame is mounted for lateral reciprocation upon the shaft 11. To this end a pair of approximately U-shaped yokes 19 are attached to the frame 18 in any suitable manner at the lateral edges thereof, the cross bar 20 of the yoke to which the arms 19 are riveted being apertured for the passage of the shaft 11. The cross bars of the yokes are spaced from each other, and disposed between these yokes and embracing the shaft 11 is a lever 21 which embraces the shaft 11 and extends downward on each side thereof. Washers 22 surround the shaft 11 and are disposed between the edges of the lever 21 and the cross bars 20 of the yokes. This lever 21 is pivoted at 23 upon a stud supported on brackets 24 extending across the frame. It will, therefore, be obvious that when the lower end of the lever 21 is operated, the frame 18 supporting the series of screens will be oscillated laterally back and forth upon the shaft 11. The frame 18 is provided upon its under side with bearings 26 through which the shaft 11 passes, these bearings permitting longitudinal movement of the frame 18 longitudinally of the shaft but also permitting a rocking movement of the series of trays supported by the frame 18 upon the shaft. The shaft 11 extends through the side walls of the casing 10, and disposed against the inner face of each side wall is a washer 27. Carried upon the adjacent end of the shaft are washers 28, and disposed between these washers are the coiled compression springs 29, these springs acting as buffers as the trays are laterally oscillated, taking up the shock of these trays.

For the purpose of oscillating these trays by power, I provide a motor, preferably an electric motor, 30 which is disposed within the inside of the casing below the trays, the motor shaft 31 carrying at its end a band wheel. A counter-shaft 32 mounted within the casing supports a band wheel 33 and a band 34 passes from the motor shaft around this relatively large wheel 33. Mounted upon the shaft 32 and rotating therewith is a band wheel 34^a which is smaller than the band wheel 33 and this is connected by means of a band 35 to a band wheel 36 mounted upon a countershaft 37. This shaft is mounted in the end wall of the cas-

ing 10 and in the intermediate wall 25 and carries upon its inner end the crank 38 having a wrist pin 39. Extending from this wrist pin 39 laterally toward the side wall of the casing 10 is a pitman 40 which at its end is connected to a link 41 pivoted at 42 upon the partition 25, and extending from the lower end of this link is a second link 43, which in turn is pivoted to the lower end of the lever 21. Thus it will be obvious that as the shaft 37 is rotated the lever 21 will be oscillated, and the upper end of this lever being engaged with the yokes 19 and 20 will cause the lateral movement of the frame 18 supporting the several screens.

As before remarked, the frame 18 is mounted upon the shaft 11 for rocking movement so that after the coins have been assorted by a shaking movement transmitted to the several coin screens, the coins may be discharged from the several screen trays and it is to this end that the frame 18 has the bearings 26 which embrace the shaft 11.

For the purpose of normally holding the screen frame in a horizontal position while it is being oscillated, I mount upon the shaft 11 a rectangular supporting frame, designated generally 44, and this frame at its ends carries the transversely extending end piece 45 slotted, as at 46, and mounted in these slots are the supporting rollers 47 against which the bottom 17 of the lowest tray bears. This frame 44 is fastened rigidly to the shaft 11 so that while the shaft 11 is held in its normal position the series of trays cannot be tipped. When, however, the shaft is rocked the frame 44 will rock with the shaft and this will act to tilt the trays from their normal position to a discharging position, as illustrated in dotted lines in Figure 2.

For the purpose of tilting the trays, the shaft 11 at one end carries a handle 48 which is adapted to be depressed to depress the forward end of the tray. For the purpose of supporting the trays for lateral reciprocation when the trays have been tilted, I mount between the sides of the casing 10 adjacent the forward ends of the trays but below the same the cross bar 49. This cross bar carries upon its upper edge face the plate 50 and also carries mounted upon it the brackets 51 which support the rollers 52. When the trays are tilted to the position shown in dotted lines in Figure 2, the forward portion of the bottom 17 of the lowest tray rests upon these rollers so that the tray is thus supported by the rollers 52 and by the shaft 11 while it is being oscillated and while it is also tipped. When the series of trays are in a horizontal position, they are supported by the shaft 11 and the frame 45 and also by a roller 53 which is mounted in a suitable bearing in the end wall 54 of the casing, the roller projecting sufficiently

so that the rear end of the bottom 17 will rest upon this roller.

Swingingly mounted within the several trays are the gates 55, 56 and 57. These are 5 disposed above the discharge ends of the several screens and when these several screens are in a horizontal position the gates are vertical and prevent any outward movement of the coins. These gates are positively 10 swung to a vertical position when the trays are in a horizontal position and positively swung outward with reference to the bottoms of the several trays when the trays are shifted to an inclined position by means 15 of the mechanism illustrated in Figure 5. Each tray is formed with a shaft 58, and carried upon each shaft is an arm 59. These arms are arranged one above the other, as illustrated in Figure 5, and pivotally connected 20 at their free ends by means of a link 60. Thus the arms will have parallel movement. Also pivotally connected to the upper link 59 is a vertical rod 61 having a foot 62 at its lower end adapted to strike against 25 an abutment 63, this rod passing through a guide 64. A contractile spring 65 which is attached to the side of the frame at one end and at its other end is connected to the arm 59 acts not only to yieldingly draw the several 30 trays to a horizontal position but also acts to resist the relative upward movement of the arms 59. When the trays are swung downward into an inclined position the lower end of the rod 61 will strike the abutment 63 and thus prevent the downward movement of the arms 59 and hold these arms in a horizontal position while the trays are moving to a downwardly inclined position. Thus the shafts 58 will be rotated 35 relative to the several trays and as the trays move downward the gates 55, 56 and 57 will be opened to permit the discharge of coins from the several trays toward the discharge ends of the trays.

It will be noted from Figure 2 that the bottom of the first tray 15 projects out beyond the bottom 16 of the second tray and this in turn projects out beyond the bottom 17 of the third tray and if more trays are 40 used they will all be arranged in this stepped relation. Operatively pivoted at the discharge end of each tray is a swinging gate or valve 66 which normally swings to a closed position but which as the trays are 45 tilted downward maintains its vertical position and thus permits the discharge of the coins from the several screens.

Coacting with each of these screens 15, 16 and 17 are the discharge chutes 67, 68 50 and 69. These are arranged in stepped relation, and as the series of trays swing downward to the discharge position the discharge end of each tray will approximate and be disposed immediately over the corresponding chute 67, 68 or 69 and the coins upon that

tray or screen will be discharged into the approximate chute. The chute 67 leads laterally downward and discharges through the spout 67^a in one side wall of the machine. The spout 68 which receives the coins from 70 the screen 16 discharges into the spout 68^a and discharges these coins at the front of the machine. The screen 17 discharges into the chute 69 and this discharges laterally into the spout 69^a. Thus it will be 75 seen, assuming this separator and assorter is designed to be used for the purpose of separating and assorting quarters, dimes and nickels, that the quarters will be discharged into the chute 67 and out through the spout 80 67^a, the nickels will be received upon the screen 16 and discharged downward into the chute 68 and through the spout 68^a, while the dimes will be received upon the screen 17, discharged into the chute 69 and thus 85 through the spout 69^a. Obviously if a greater number of denominations of coins are to be separated there will be more screens, as before explained, a corresponding number of chutes, and a corresponding number of spouts.

I have illustrated in Figure 7 the arrangement of the screens, chutes and the spouts for a machine capable of handling coins including half dollars, quarters, nickels, dimes 90 and pennies. This is merely to illustrate that my coin separating device may be so arranged as to separate mixed coins including coins of a plurality of denominations without in any way departing from the principle of the invention.

The coins are disposed upon the top tray and heaped onto the screen thereof. This screen has perforations 70 therein of such size as to prevent the downward passage 100 therethrough of the largest coins which are to be separated but permitting all coins of a smaller diameter to pass. Thus, for instance, all the quarters will be held upon the screen 15. The screen 16 is provided with 110 perforations 70 large enough to retain the next largest size of coins as, for instance, nickels and allow all the smaller coins to drop through. Thus in Figure 4 the dimes will drop through the screen 16 and onto 115 the bottom plate 17. If other coins are to be distributed, obviously the plate 17 will be perforated and the smallest coin will pass through these perforations.

For the purpose of preventing the heap of 120 coins from being shaken out or off of the upper tray, I provide the side walls of this tray at the rear end where the coins are initially placed with overhanging flanges 71 and also provide a cover 72 which may be 125 disposed upon the case 10 so as to cover in the top thereof. Preferably in addition to the springs 29 buffers 73 of rubber or like resilient material are disposed against the side walls of the machine and surround the 130

shaft 11, these buffers assisting in taking the impact of the trays when the latter are reciprocated.

Of course, it will be understood that any proper connections may be made from the motor 30 to a source of electric current and that a switch is used to control the motor 30. Obviously also any other form of prime mover might be used in place of the motor 10 and it is within the purview of my invention to provide the driving shaft of the machine with a crank handle instead of a motor whereby it may be operated. I have found, however, that where large numbers of coins 15 are to be assorted that the motor is particularly convenient.

The operation of the mechanism will be obvious from what has gone before. As soon as the circuit is closed through the 20 motor the series of trays are oscillated by the mechanism heretofore described and this causes the coins which are heaped upon the upper tray or screen to be joggled down little by little and to drop through the openings 70 in this tray onto the next subjacent tray and so on until all the coins have been distributed in their respective trays, the gates preventing the coins from moving forward along the trays before they have 25 dropped through the apertures 70 and the sides of the tray preventing the coins from passing outward into the sides between the trays and the casing. When the coins have been fully assorted the shaft 11 is rocked to 30 tilt the trays without, however, interrupting the lateral reciprocation of the trays so that the coins which are disposed within the several trays and on the screens will be joggled downward until they are discharged in 35 the discharge ends of the screens. As soon as the trays are tilted to the position where the coins will be discharged by the action of gravity and the oscillation given to the trays, the gates 55, 56 and 57 will be opened and 40 the coins discharged into the chutes. The swinging gate 66 will prevent the coins from being discharged beyond the chutes 68 and 69. Of course, when the coins are discharged into the chutes they will fall by gravity 45 down to their respective spouts and be discharged in suitable receptacles arranged there for the purpose of catching the coins. When the coins have all been discharged the 50 lever is lifted, returning the trays to their horizontal positions ready for a second supply of coins.

The mechanism is particularly applicable for all those concerns which receive a large 55 number of small coins during the day and particularly useful for banks, street car companies, moving picture theatres, telephone companies, and the like. Obviously the machine may be made of any suitable dimensions and, therefore, it will be adapted to 60 separate a large number of different coins at

a time. Obviously the mechanism might be changed in many ways without departing from the spirit of the invention as defined in the appended claims.

I claim:

1. A coin assorber and separator including a supporting frame, a series of superposed trays carried therein, the trays having differential perforations in their bottoms, means for shaking the trays to thereby cause 75 the coins to joggle through the apertures in the trays, means whereby the trays may be tilted to discharge the coins from the forward ends thereof, and gates mounted in connection with the trays and adapted to 80 close the forward ends of the tray when the tray is in a horizontal position, the tilting movement of the trays acting automatically to open the gates.

2. A coin assorber and separator includ- 85 ing a supporting frame, a series of super- posed trays carried therein, each tray having a bottom and the bottom of the lowest tray being imperforate, the trays above having perforated bottoms, the bottom of a lower 90 tray having perforations smaller than the bottom of the tray immediately above, gates adapted to close the forward ends of the trays when the trays are in a horizontal position to thereby prevent the dislodgment of 95 coins therefrom, means for laterally recip- rocating the trays to cause the distribution of coins thereover, and means whereby the trays may be tilted to discharge the coins, the tilting movement of the trays acting to 100 open the gates.

3. In a coin separator and assorber, a supporting frame, a series of superposed coin trays disposed within the frame, the bottom of the lowest tray being imperforate, 105 the bottoms of the superjacent trays being perforate and the perforations of one tray being larger than the perforations of the tray next below, the forward ends of the trays being open for the purpose of dis- 110 charging coins, gates pivoted upon the side walls of each tray and hanging vertically downward when the trays are in a hor- 115 izontal position to prevent the dislodgment of the coins from the trays, means for re- ciprocating the trays laterally, means where- 120 by the trays may be tilted to discharge the contents thereof while the trays are being reciprocated, and means for automatically opening said gates when the trays are tilted downward and causing the gates to posi- 125 tively close when the trays are raised to a horizontal position.

4. A coin separating and assorting mecha- 125 nism comprising a supporting frame, a series of superposed trays disposed within the frame, the bottom of the lowest tray being imperforate, each superjacent tray hav- 130 ing its bottom perforated and the perfora- tions of one tray being smaller than the

- perforations of the tray immediately above, a gate swingingly mounted upon each tray and preventing the discharge of coins longitudinally therethrough, means for laterally reciprocating the series of trays, manually operable means whereby the trays may be tilted to discharge the coins, means acting to raise said gates when the trays are tilted downward, and a series of chutes into which the trays respectively discharge.
5. A coin separating and assorter comprising a supporting frame, a series of superposed trays disposed within the frame, the bottom of the lowest tray being imperforate, each superjacent tray having its bottom perforate and the perforations of one tray being smaller than the perforations of the tray immediately above, a gate swingingly mounted upon each tray and preventing the discharge of coins longitudinally therethrough, means for laterally reciprocating the series of trays, manually operable means whereby the trays may be tilted to discharge the coins, means acting 10 automatically to raise said gates when the trays are tilted downward, a series of chutes into which the trays respectively discharge, and swinging gates at the discharge ends of the trays swinging over said chutes as the trays are tilted downward to prevent the coins from passing beyond the chutes.
6. A coin separator and assorter comprising a supporting frame, a series of trays disposed within the frame, the lowest tray having an imperforate bottom, the other trays having perforate bottoms, the apertures of one tray being smaller than the apertures of the tray immediately above, a shaft supporting the trays for tilting movement, means for preventing the discharge of coins from the trays when they are in a horizontal position and automatically opening to permit the discharge of coins when the trays are in their tilted position, supporting means carried by the shaft and oscillatable therewith and upon which the trays rest, the trays having lateral movement relative to the shaft and said supporting means, and means for laterally reciprocating the trays.
7. A coin separator and assorter comprising a supporting frame, a series of trays disposed within the frame, the lowest tray having an imperforate bottom, the other trays having perforate bottoms, the apertures of one tray being smaller than the apertures of the tray immediately above, a shaft supporting the trays for tilting movement, means for preventing the discharge of coins from the trays when they are in a horizontal position and automatically opening to permit the discharge of coins when the trays are in their tilted position, supporting means carried by the shaft and oscillatable therewith and upon which the trays rest, the trays having lateral movement lengthwise of the shaft, coiled springs disposed between the trays and the frame and resisting lateral movement of the trays, means carried by the shaft for supporting the trays in a horizontal position and permitting said lateral reciprocation and causing the tilting of
- trays rest, the trays having lateral movement relative to the shaft and said supporting means, and power operated means for laterally reciprocating the trays including a power driven crank, and a pitman connected to the trays.
8. A coin separator and assorter comprising a supporting frame, a series of trays disposed within the frame, the lowest tray having an imperforate bottom, the other trays having perforate bottoms, the apertures of one tray being smaller than the apertures of the tray immediately above, a shaft supporting the trays for tilting movement, means for preventing the discharge of coins from the trays when they are in a horizontal position and automatically opening to permit the discharge of coins when the trays are in their tilted position, supporting means carried by the shaft and oscillatable therewith and upon which the trays rest, the trays having lateral movement relative to the shaft and said supporting means, means for laterally reciprocating the trays, and means for cushioning the trays at their terminations of the reciprocating movement.
9. A coin separator and assorter comprising a supporting frame, a series of trays disposed within the frame, the lowest tray having an imperforate bottom, the other trays having perforate bottoms, the apertures of one tray being smaller than the apertures of the tray immediately above, a shaft supporting the trays for tilting movement, means for preventing the discharge of coins from the trays when they are in a horizontal position and automatically opening to permit the discharge of coins when the trays are in their tilted position, supporting means carried by the shaft and oscillatable therewith and upon which the trays rest, the trays having lateral movement relative to the shaft and said supporting means, means for laterally reciprocating the trays, and means for cushioning the trays at their terminations of the reciprocating movement including coiled compression springs surrounding said shaft and normally urging the trays to a middle position on the shaft.
10. A coin separator and assorter comprising a supporting frame, a series of superposed trays disposed within the frame, the lowest tray of the series having an imperforate bottom, the remainder of the trays having perforated bottoms, a manually operable transverse rock shaft mounted in the frame, the series of trays having bearings through which the shaft passes, the bearings permitting reciprocation of the trays lengthwise of the shaft, coiled springs disposed between the trays and the frame and resisting lateral movement of the trays, means carried by the shaft for supporting the trays in a horizontal position and permitting said lateral reciprocation and causing the tilting of

the trays when the shaft is rocked in one direction, a lever embracing the shaft and movable longitudinally of the shaft, yokes operatively connected to the trays and bearing loosely against said lever on each side of said lever, and power operated means for oscillating the lever.

11. A coin separator and assorter including a supporting frame, a series of superposed trays disposed within the frame, the lowermost tray having an imperforate bottom, the superjacent trays having perforate bottoms, the apertures in the bottom of one tray being larger than the apertures of the tray immediately below, a manually operable transverse rock shaft carried in said frame, bearings carried by the trays and through which the shaft passes, said bearings permitting the lateral movement of the trays with relation to the shaft, a frame mounted upon the shaft for rocking movement therewith and extending beneath the trays and having rollers upon which the bottom of the lowest tray engages, rollers mounted upon the frame below the forward end of the tray and with which the forward end of the tray engages when the rock shaft is rocked and the trays tilted to a discharge position, and means for laterally reciprocating the trays including a crank, and a lever operated by the crank and embracing the shaft and being oscillatable independently of the shaft, and yokes engaging on opposite sides of the lever and loosely surrounding the shaft and connected to the trays.

12. A coin separator and assorter including a supporting frame, a series of superposed trays disposed within the frame, the lowermost tray having an imperforate bottom, the superjacent trays having perforate bottoms, the apertures in the bottom of one tray being larger than the apertures of the tray immediately below, a manually operable transverse rock shaft carried in said frame, bearings carried by the trays and through which the shaft passes, said bearings permitting the lateral movement of the trays with relation to the shaft, a frame mounted upon the shaft for rocking movement therewith and extending beneath the trays and having rollers upon which the bottom of the last tray engages, rollers mounted upon the frame below the forward end of the tray and with which the forward end of the tray engages when the rock shaft is rocked and the trays tilted to a discharge position, means for laterally reciprocating the trays including a crank, a lever operated by the crank and embracing the shaft and being oscillatable independently of the shaft, yokes engaging on opposite sides of the lever and loosely surrounding the shaft and connected to the trays, and a roller mounted at the rear end of the frame and upon which the rear end of

the series of trays rest when the trays are in a horizontal position and constituting a stop limiting the movement of the trays in either direction.

13. In an assorting mechanism of the character described, a series of trays mounted for tilting movement, swinging gates mounted upon each tray and normally extending across the path of movement of the contents of the tray, the gates having shafts extending to the exterior of the several trays, parallel link connected arms mounted upon the shafts, a rod connected to one of said arms and extending vertically downward, an abutment with which said rod is adapted to engage as the trays swing downward to thereby cause the opening of the gates, and a spring yieldingly urging the arms on the several gates to a horizontal position.

14. A coin assorting mechanism of the character described including an outer casing having a cover, a series of superposed trays disposed in the upper portion of said casing and supported in a frame, the lowest tray having an imperforate bottom, superjacent trays being formed with perforate bottoms and the perforations in one tray being less in size than the perforations in the tray next above, the trays being closed at their rear ends, gates adjacent the forward ends of the trays preventing the discharge of coins therefrom when the trays are in a horizontal position, a transverse shaft, the tray frame having bearings through which said shaft loosely passes, a frame supported by said shaft for oscillation therewith extending beneath the trays and having rollers at its opposite ends against which the bottom of the lowest tray rests, a lever loosely embracing the shaft, yokes attached to the tray frame loosely embracing the shaft and bearing against opposite sides of the lever, power operated means for oscillating the lever to thereby reciprocate the trays, resilient buffers resisting the reciprocation of the trays, rollers operatively supported below the forward ends of the trays and upon which the bottom of the lowest tray rests when the trays are tilted to a discharge position by operating said lever, means for raising said gates when the trays are tilted, the forward ends of the trays being disposed in stepped relation, chutes disposed below the forward end of each tray, the several chutes being disposed in stepped relation whereby as the series of trays are tilted each tray will have its mouth disposed over one of said chutes, and spouts opening upon the exterior of the casing and into which said chutes discharge.

In testimony whereof I hereunto affix my signature.

ADDREN H. YOUNG.
